UNITED STATES PATENT OFFICE.

FRIEDRICH WILHELM SCHUBERT, OF APPERLEY BRIDGE, NEAR BRADFORD, ENGLAND, ASSIGNOR TO BRYSLKA, LIMITED, OF APPERLEY BRIDGE, NEAR BRADFORD, ENGLAND.

VARIABLE-CAPACITY PUMP.

Application filed June 21, 1926, Serial No. 117,534, and in Great Britain July 2, 1925.

This invention relates to the manufacture of artificial silk and in particular to improvements in pumps for use in fluid pumps for supplying cuprammonia cellulose solutions to spinning machines or to the spinning nozzles thereof, the chief object being to provide a pump wherein no gas or air pockets are afforded in the pump and great accuracy is ensured.

According to the invention we employ a pump of the type comprising a casing having an inlet and an oppositely situated outlet and within which is provided a cylindrical rotary member having a series of radial slots adapted to carry a series of radially disposed members slidably mounted therein, the said slidably mounted members being provided with laterally projecting pins or runners adapted to engage eccentric tracks or grooves formed in the side cover plates of the casing so as to cause the said series of slidably mounted members to be moved inwardly toward the centre and then outwardly toward the periphery of the rotary member during each complete revolution thereof.

In order that the invention may be clearly understood and readily carried into effect, the same will now be more fully described with reference to and by aid of the accompanying drawings: wherein:—

Figure 1 is a side elevation of a fluid pump of the type employed in accordance with the invention, a portion of the side cover plate being broken away for the sake of clearness.

Figure 2 is a plan view of Figure 1.

Figure 3 is a half end elevation and half transverse section of Figure 1.

Figure 4 is a part transverse section taken through one of the radial and slidable members of the cylindrical rotary member.

Referring to the drawings, 1 is the pump casing having an inlet 2 and an oppositely situated outlet 3, and within the casing 1 is provided a cylindrical rotary member 4 having a series of radial slots or recesses 5 which have a series of radially disposed members 6 slidably mounted therein, said slidably mounted members 6 being provided with laterally projecting pins 7 which carry runners 8 adapted to engage eccentric tracks or grooves 9 formed in side cover plates 10 of the casing 1 so as to cause the said slid-

able members 6 to be moved inwardly toward the centre and then outwardly toward the periphery of their rotary carrying member 4 during each complete revolution thereof.

The inlet orifice 2 may have associated therewith a feed control device in the form of a conical-ended screw operated plunger (not shown) adapted to be adjustably positioned in relation to said inlet orifice 2 of the casing 1, so as to control the flow of viscous liquid to the latter from the main feed pipe (not shown), to which the pump is connected. The rotary member 4 is formed with an integral central spindle or shaft 11 by which it is mounted in bearings 12 in the side cover plates 10 of the casing 1, and said rotary member 4 is adapted to be driven through the medium of a toothed wheel 13 secured on said spindle or shaft 11, the speed of rotation being in accordance with the desired rate of flow of liquid from the outlet.

The radial movement of the slidably mounted members 6, during the revolution of their rotary carrying member 4, has the effect of drawing the viscous liquid, which is fed under pressure into the pump, into the radial slots or recesses 5, of the rotary member 4 as each slidably mounted member 6 passes the inlet orifice 2 and then expelling the viscous liquid from said slots or recesses 5, as they pass the outlet 3.

The side cover plates 10 are rotatably mounted within flange rings 13¹ on the sides of the pump casing 1, and are each provided with pivotally mounted links 14 secured together at their outer extremities by a cross-head 15 carrying an adjustable screwed spindle 16 adapted by means of fixed collars 17 thereon to engage a fixed depending member 18 secured to the upper part of the casing; the arrangement being such that, by rotation of the screwed spindle 16, the side cover plates 10 may, through the cross-head 15 and links 14, be rotated through a small angle in either direction so as to vary the position of maximum throw of the eccentric tracks 9 in relation to the outlet 3, thereby enabling fine adjustment or regulation of the delivery to be made.

I claim:—

1. In a pump of the character described,

- the combination of a casing provided with inlet and outlet openings, a rotor within the casing having a plurality of chambers adapted to successively come into communication 5 with the inlet and outlet openings of the casing as the rotor turns, a piston in each of said chambers having a stem extending radially of the rotor, cam plates arranged at opposite sides of the rotor and cooperating 10 with the piston plungers to effect reciprocation of the pistons as the rotor turns, and means for rotatively adjusting said cam plates about the axis of the rotor, for the purpose described.
- 15 2. In a pump of the character described, the combination of a casing provided with inlet and outlet openings, a rotor within the casing having a plurality of chambers adapted to successively come into communication 20 with the inlet and outlet openings of the casing as the rotor turns, a piston in each of said chambers having a stem extending radially of the rotor, plates arranged at opposite sides of the rotor and provided in their 25 opposed faces with parallel cam shaped grooves, lateral projections on the piston stems extending into said grooves, whereby the pistons will be reciprocated as the rotor turns, and means for rotatively adjusting said plates about the axis of the rotor, for the purpose described. 30
3. In a pump of the character described, the combination of a casing provided with inlet and outlet openings, a rotor within the casing having a plurality of chambers adapted to successively come into communication 35 with the inlet and outlet openings of the casing as the rotor turns, a piston in each of said chambers having a stem extending radially of the rotor, cam plates arranged at opposite sides of the rotor and cooperating 40 with the piston plungers to effect reciprocation of the pistons as the rotor turns, parallel links each connected to one of the cam plates, a cross head connecting said links, and a screw projecting from the casing and engaging the cross head, whereby by turning the screw the cam plates may be bodily adjusted 45 rotatively about the axis of the rotor, for the purpose described.

FRIEDRICH WILHELM SCHUBERT.
